UNITED STATES PATENT OFFICE.

THEODORE GENTZSCH, OF BROOKLYN, NEW YORK, ASSIGNOR TO HIMSELF AND GUSTAVE A. WITTE, JR., OF SAME PLACE.

HOLDER FOR COLLARS OR CUFFS.

SPECIFICATION forming part of Letters Patent No. 361,058, dated April 12, 1887.

Application filed August 30, 1886. Serial No. 212,241. (No model.)

To all whom it may concern:

Be it known that I, THEODORE GENTZSCH, of the city of Brooklyn, in the county of Kings and State of New York, have invented a new and Improved Holder for Collars or Cuffs, of which the following is a full, clear, and exact description.

My invention relates to holders for collars or cuffs, and has for its object to produce a simple holder, quickly and easily applied, which will securely attach either a collar or cuff to the proper band of a shirt.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 illustrates my holder as applied to a cuff, and Fig. 2 is a side elevation thereof. Fig. 3 illustrates the application of my holder to a collar, and Fig. 4 is a side elevation of the contracted holder applied in Fig. 3.

The body of my fastener is usually constructed of one piece of metal, made S shape, the two legs A, A' thereof being of equal length, while the leg B is made shorter.

Near the curved end of the leg A, I pivot a swinging arm, C, preferably made in loop form, as shown in Fig. 2, in which one side thereof, c, is made straight, the other side, c', being bowed and provided with an inwardly-curved surface at its pivotal end. The said side c' is thus formed to receive a slightly-curved projecting pin, D, which is attached thereto. The bowed side c' of the swinging arm C need not necessarily extend downward to a connection with the body of the fastener. If desired, it may be broken off at any point below the top of said arm C. As the swinging arm C is carried over the leg A of the S-shaped body, as shown by the arrow in Fig. 2, the pin D is adapted to pass one side of the said leg A and enter its point beneath the shield d, secured to the central leg, A', of the said S-shaped body immediately opposite the said swinging arm C.

A second swinging arm, E, preferably simi-

lar in construction to the upper swinging arm, C, is pivotally attached to the end of the short leg B of the fastener, adapted to be operated in like manner to said upper swinging arm, but in an opposite direction, as indicated by the lower arrow, Fig. 2, the pin e of the lower swinging arm, E, entering a shield, F, attached parallel therewith to the lower end of the central leg, A.

When the fastener is used to hold a cuff, the swinging arms are opened, as in Fig. 2, and the wristband of the shirt is made to engage the space between the legs A and A' of the S-shaped body, with the leg A' projecting downward outside the sleeve. The upper pivoted swinging arm, C, is now pushed forward, and the pin D, piercing the band, enters the shield d, retaining the fastener in position. The cuff is now entered between the short leg B and the central leg, A', and the lower swinging arm, E, pressed inward, whereupon the said cuff is held securely within the fastener by the entering pin e, as shown in Fig. 1.

When used with a collar, the S-shaped body is made with its legs G, H, and K short and of equal length, and instead of looped arms the solid swinging arms M, M' are preferably employed, provided with small looped offsets m at the free ends thereof, purposed to afford a convenient purchase for the fingers when the fastener is applied.

The swinging arm M is pivoted at one side to the upper end of the leg K, the attached pin of the said swinging arm M being adapted to enter a shield, N, secured upon the same side near the center of the leg H.

Upon the opposite side of the fastener the swinging arm M' is pivoted to the upper end of the central leg, H, its attached pin being adapted to enter the shield N', secured to the leg G upon the same side of the fastener as that upon which the said swinging arm M' is pivoted.

In the application of the fastener to a collar the neckband is made to enter the space between the legs G and H, and the said fastener is held thereto by the engagement of the pin n' of the swinging arm M'. The two ends of the collar are now entered into the space between the legs H and K, and are engaged and held in proper position by the pin n of the front swing-

an S-shaped body having two legs, A and A', of equal length, and one short leg, B, the said leg A having attached thereto at top and bottom shields d and F, together with a swinging arm, C, carrying a pin, D, pivoted to the leg A, and a similar swinging arm, E, provided with a pin, e, pivoted to the short leg B, substantially as shown and described, and for the purpose set forth.

The body of the fastener may be provided with either solid swinging arms, as shown in Fig. 4, or looped, as in Fig. 2, without departing from the spirit of my invention.

Having thus described my invention, what I claim as new, and desire to secure by Letters

to Patent, is—

1. A collar or cuff fastener consisting of an S-shaped body having swinging arms carrying pins, substantially as shown and described, and for the purpose herein set forth.

15 2. A collar or cuff fastener consisting of an S-shaped body having swinging arms carrying pins, together with shields attached to said body, adapted to receive said pins, substantially as shown and described, and for the purpose herein set forth.

20 3. A collar or cuff fastener consisting of

an S-shaped body having two legs, A and A', of equal length, and one short leg, B, the said leg A having attached thereto at top and bottom shields d and F, together with a swinging arm, C, carrying a pin, D, pivoted to the leg A, and a similar swinging arm, E, provided with a pin, e, pivoted to the short leg B, substantially as shown and described, and for the purpose set forth.

25 4. In a collar or cuff fastener, the combination, with the S-shaped body consisting of the legs A A', of equal length, and shorter leg, B, together with the shields d and F, secured to said body, of the swinging arms C and E, carrying pins D and e, substantially as shown and described, and for the purpose set forth.
